UNITED STATES PATENT OFFICE.

ARTHUR CYROUS SMITH, OF COLORADO SPRINGS, COLORADO, ASSIGNOR, BY MESNE ASSIGNMENTS, OF ONE-HALF TO WILLIAM W. HASSELL AND ONE-HALF TO ARTHUR C. SMITH, BOTH OF COLORADO SPRINGS, COLORADO.

COMBINED ATOMIZER AND VAPORIZER FOR OIL ENGINES.

Application filed July 12, 1920. Serial No. 395,709.

To all whom it may concern:

Be it known that I, ARTHUR CYROUS SMITH, a citizen of the United States, and a resident of Colorado Springs, in the county 5 of El Paso and State of Colorado, have invented certain new and useful Improvements in Combined Atomizers and Vaporizers for Oil Engines, of which the following is a specification.

10 My invention relates generally to internal combustion engines burning hydro-carbon oils and particularly to a combined atomizer and vaporizer for converting fuel oil into gas.

15 A purpose of my invention is the provision of an atomizer and vaporizer in which the vaporizing member is so constructed and arranged within a cylinder as to permit of the direct application of an exterior source 20 of heat thereto whereby a rapid and efficient initial heating of the member can be effected.

Furthermore, my invention provides a vaporizing member which uniformly distributes the fuel vapor throughout the explosion end of the cylinder, such member in its applied position being subjected to uniform pressure throughout its area to allow of the use of a comparatively light and inexpensive construction capable of withstanding 25 all pressures without distortion.

30 A further purpose of my invention resides in the provision of an atomizer and vaporizer in which the atomizing member effects a thorough atomization of the fuel as it enters a cylinder and directs the same into the vaporizing member in a manner to assist the latter in uniformly distributing the vaporized fuel within the cylinder.

35 I will describe two forms of device embodying my invention, and will then point out the novel features thereof in claims.

In the accompanying drawings:

Figure 1 is a view partly in longitudinal section showing a conventional form of oil 40 engine having applied thereto one form of combined atomizer and vaporizer embodying my invention.

Figure 2 is an enlarged detail view showing in longitudinal section the atomizing member and a portion of the vaporizing member shown in Figure 1.

Figure 3 is a view showing in end elevation, the atomizing member shown in Figures 1 and 2.

Figure 4 is a transverse sectional view 55 taken on the line 4-4 of Figure 2.

Figure 5 is a transverse sectional view taken on the line 5-5 of Figure 1.

Figure 6 is a view similar to Figure 1 showing another form of cylinder head and 60 vaporizing member embodying my invention.

Figure 7 is a transverse sectional view taken on the line 7-7 of Figure 6.

Similar reference characters refer to 65 similar parts in each of the several views.

Referring specifically to the drawings and particularly to Figures 1 and 2, the combined atomizer and vaporizer forming the subject matter of my invention essentially consists of an atomizing member and a vaporizing 70 member, the former being designated generally at A and comprising a body 15 preferably formed of steel, a nozzle 16, an atomizing block 17 and a valve 18. As illustrated to advantage in Figure 2, the body 75 15 is formed with a longitudinally extending duct 15^a which communicates at one end with an oil supply pipe 19, the latter in turn communicating with an oil injecting pump (not shown) of any standard form. The opposite end of the duct 15^a communicates with a chamber 15^b, the lower end portion of which is of an increased diameter with its wall threaded to receive the nozzle 16. The nozzle 16 is of cup-formation with its lower 85 end wall formed with a circular series of perforations 16^a, all of which are inclined outwardly from the axis of the nozzle for a purpose which will be hereinafter described. Within the nozzle 16 is fitted the 90 atomizing block 17, such block being of circular formation as shown in Figure 4 and provided at intervals upon its periphery with longitudinally extending channels 17^a. The opposite ends of the block 17 are formed 95 exteriorly thereof with pins 17^b and 17^c, the pin 17^b reposing upon the upper side of the lower end wall of the nozzle 16 and thus maintaining the block in spaced relation to the lower end of the nozzle. This arrangement permits of the free passage of the fuel oil from the channels 17^a to and through the perforations 16^a as will be more fully described.

100 The upper pin 17^c is embraced by and serves to position a coiled expandible spring 20. The upper end of the spring 20 supports and urges the valve 18 into engagement with a valve seat 15^c formed at the 105

junction of the duct 15^a and the chamber 15^b. As clearly shown in Figure 2, the valve 18 is of the ball type, and under the action of the spring 20 normally occupies the seat 15^c so as to close the lower end of the duct 15^a.

The vaporizing member is designated generally at V and as shown in Figures 1 and 5 comprises an outer tube 21 and an inner tube 22, snugly fitted within the outer tube with one end projecting beyond the corresponding end of the outer tube, and its opposite end terminating at such a point that when in applied position within the cylinder head of an oil engine that it will coincide with the axis of the cylinder head. As shown in Figure 5, the tubes 21 and 22 are formed with registering perforations 23 through which the vaporized oil leaves the vaporizing member and enters the combustion end of the cylinder of an oil engine. As shown in Figure 1, the outer tube 21 is formed at one end with an outwardly flared annular lip or flange 22^a which is adapted to be engaged by a screw plug 24 for securing the vaporizing member as a unit within the cylinder head of an engine. The screw plug 24 is provided with an extension 24^a which is formed with an opening to slidably receive an actuating handle 25, which is adapted to be gripped in actuating the plug, as will be understood.

In Figure 1 I have illustrated a conventional form of oil engine, the cylinder head 35 of which is provided at diametrically opposite points with suitable openings for the reception of the atomizing and vaporizing members. In the applied position of the atomizing and vaporizing members to the cylinder head of the oil engine, the vaporizing member is inserted through the largest opening of the cylinder head so that it extends almost entirely across the bore of the cylinder. The opening for the vaporizing member is formed with an annular shoulder against which the lip 22^a is adapted to be held by the screw plug 24. The atomizing member A is threadedly fitted within the other opening of the cylinder head, a nut 15^d being formed on the outer end of the body 15 to facilitate the application or removal of the atomizing member to or from the cylinder head as will be understood. As applied, the nozzle 16 of the atomizing member 55 is partly inserted into the adjacent end of the vaporizing member with the perforations 16^a extending in the direction of the inner wall of the tube 22.

In operation, an initial heating of the vaporizing member is effected by first removing the plug 24 and then inserting a lighted torch directly into the member. After the vaporizing member has been heated to a proper degree, the torch is removed and the plug 24 replaced so that the

engine is now ready to start. Fuel oil is now introduced into the atomizing member through the pipe 19 under such pressure as to effect an opening of the valve 18. The oil, after traversing the duct 15^a enters the chamber 15^b and from the chamber 15^b passes through the several channels 17^a of the atomizing block 17. During the passage of the oil through the channels 17^a, a subdivision of the oil into minute particles is effected so that when it leaves the nozzle through the perforations it is in the form of a spray. From the nozzle 16 this oil spray impinges upon the inner wall of the inner tube 22, and the latter being sufficiently heated causes the spray to be converted into a vapor which when mixed with a sufficient quantity of air introduced into the cylinder through another source (not shown) produces an explosive mixture which is ignited when the piston reaches the end of its compression stroke. As the piston advances on its compression stroke, the vaporized fuel within the vaporizing member is ejected through the several perforations 23 where it is uniformly mixed with the air throughout the area of the cylinder head thereby producing a high explosive mixture which, as previously explained, is ignited when the piston reaches the end of its compression stroke. After the vaporizing member has been initially heated to effect the initial explosion of the gaseous mixture, it continues to be heated by the explosions in the cylinder. By virtue of the inner tube 22, a greater heating of the vaporizing member is secured at its entrance end or where the atomized oil is introduced into the member. This is, of course, due to the increased thickness of the vaporizing member, with the result that, as the atomized fuel enters the vaporizing member it is immediately subjected to a heat of great intensity thereby effecting a complete vaporization of the fuel.

In practice, the nozzle 16 of the atomizing member A and the tubes 21 and 22 of the vaporizing member V are all formed of copper, it having been found that copper, when subjected to a heat of fluctuating intensity causes a continuous annealing of the copper which action serves to throw off any carbon deposits which may adhere to their surfaces.

Referring now to Figures 6 and 7, I have here shown a modified form of vaporizing member designated generally at V' and comprising a horizontal tubular portion 30 formed integral with and communicating with a vertical tubular portion 31 at a point intermediate its ends. The vertical tubular portion 31 is closed at one of its ends as shown in Figure 6, its open end receiving the nozzle 16 of the atomizing member A so as to receive the atomized fuel and effect a uniform distribution of

the same in the same manner as described in connection with the vaporizing member V.

As shown in Figure 6, the vaporizing member V' as a unit is secured in proper position within the cylinder by means of arms 32 which are formed integral with the horizontal tubular portion 30 and are provided with openings to receive bolts 33 which secure the arms to the inner side of the cylinder head in the manner shown. The horizontal tubular portion 30 extends into a hot bulb 34 which is formed integral with the cylinder head and communicates 15 with the interior of the cylinder. This arrangement permits the initial heating of the vaporizing member by first heating the hot bulb 34, such heat being transmitted to the portion 30 and from the latter to 20 the portion 31.

From the foregoing description, taken in conjunction with the accompanying drawings, it will be manifest that in both forms of vaporizing members, a uniform distribution of the vaporized fuel throughout the explosive end of a cylinder is readily effected by virtue of the manner in which the atomized fuel is introduced into the vaporizing member and the perforations formed in the walls of the latter. It will be further manifest that because of the manner in which the vaporizing member V is mounted within the cylinder head that a quick and efficient heating of such member can be easily effected as the heating medium can be directly applied to the vaporizing member.

Although I have herein shown and described only two forms of combined vaporizers and atomizers it is to be understood that various changes and modifications may be made herein without departing from the spirit of the invention and the spirit and scope of the appended claims.

4.5 What I claim is:

1. In combination, a tubular perforated vaporizing member having an annular lip formed on one end thereof, and a removable plug adapted to engage said lip whereby to secure said vaporizing member within a cylinder head and for closing said end of the vaporizer.

2. In combination, a tubular perforated member having an annular lip formed on

one end thereof, and a screw plug adapted 55 to engage said lip for securing the member within a cylinder head and for closing the said end of the member.

3. A vaporizer for oil engines comprising 60 a pair of perforated tubes arranged one within the other, the outer tube being of greater length than the inner tube, and its outer end adapted to be closed and secured within the cylinder head of the engine.

4. A vaporizer for oil engines comprising 65 a pair of perforated tubes arranged one within the other, the outer tube being of a greater length than the inner tube, and an annular flange formed on the outer end of the outer tube, whereby to secure said vaporizer in the cylinder head of the engine.

5. In combination, a vaporizing member comprising, an outer tube having a lip formed on one end thereof, an inner tube arranged within the outer tube and of a 70 length less than the outer tube, registering perforations formed in both of said tubes, and a screw plug adapted to engage said lip for supporting the vaporizing member within a cylinder head.

6. In combination, a cylinder head, a vaporizer comprising a perforated tubular member extending into said head and having open ends, one open end flared and adapted to be secured in said head, and 85 means for removably securing said flared end in the head, said flared end adapted to be initially heated.

7. In combination, a cylinder head, a vaporizer comprising a perforated tubular 90 member extending into said head and spaced from the end wall thereof and having open ends, one open end adapted to be secured in said head, removable means to secure such end in the head, said means 95 adapted to be removed to permit application of a torch into the vaporizer to effect initial heating of same.

8. In combination, a vaporizer comprising 100 a pair of perforated tubes arranged one within the other in snug fitting relation, the outer tube of greater length than the inner tube, the outer end of the inner tube projecting beyond the end of the outer tube, and means for securing the opposite end 105 of the outer tube within a cylinder head.

ARTHUR CYROUS SMITH.
